HIGHWAY SIGN

Casper Christopherson, Mukilteo, Wash.

Application May 17, 1957, Serial No. 46,210

Term of patent 7 years

(Cl. D72—1)

The wording shown in broken lines in Figure 1 is for purpose of illustration.

I claim:

The ornamental design for a highway sign, as shown and described.
